SHIRLEY R. NAYSMITH, OF CLEVELAND, OHIO, ASSIGNOR TO THE MILLER COMPANY,
OF MERIDEN, CONNECTICUT, A CORPORATION OF CONNECTICUT

LIGHTING FIXTURE

Application filed March 11, 1930. Serial No. 434,861.

The present invention relates to lighting fixtures and is more particularly directed toward improvements in lighting fixtures employing high power electric lamp bulbs for industrial illumination and wherein a glass diffuser is placed about the light source and a large metal reflector outside the diffuser acts to reflect the light downwardly.

The present invention contemplates improvements in the type of fixture shown in U. S. Patent No. 1,536,844 and more particularly in designing the fixture so that it may employ a totally enclosed glass diffuser adapted to be threaded into a supporting ring carried by the fixed parts. This threaded ring and the neck of the globe or diffuser are large enough to permit the globe or diffuser to accommodate the bulb of the lamp, and as these parts are at a comparatively large radius, considerable turning moment is brought about when the diffuser is loosened.

To make the device dust and vapor proof, it is also preferably so arranged that the neck of the threaded diffuser may be brought against a gasket.

Fixtures of this type are usually mounted in a threaded fitter or socket cover made of a casting or of porcelain enameled steel, the reflector and diffuser being supported by a threaded neck usually made of copper and adapted to be threaded into the fitter.

The present invention contemplates an arrangement whereby unthreading of the supporting neck from the fitter is not brought about by the unthreading of the glass diffuser in its support. This may be accomplished by employing gasket materials of different coefficient of friction and surface contact, so that the glass can be loosened from its support with less turning effort than is required to loosen the neck of the reflector support from the stationary fitter or socket cover.

Other and further objects of the invention will appear as the description proceeds.

The accompanying drawing shows, for purposes of illustrating the invention, one embodiment in which the invention may take form, together with modifications of certain parts, it being understood that the drawing

is illustrative of the invention rather than limiting the same.

In the drawing:

Figure 1 is an elevational view of one form of lighting fixture;

Figure 2 is a sectional view of the upper part of the fixture on an enlarged scale and with parts in elevation;

Figure 3 is a top plan view of the reflector support with part in section on the line 3—3 of Figure 2; and

Figure 4 is a fragmentary sectional view showing a modified form of construction.

The upper part of the fixture, as indicated in the drawing, comprises a socket cover or fitter 10 adapted to enclose a lamp socket 11. These parts are secured together by a left handed threaded nut 12 threaded on a stem 12' in the usual manner. The lower end or skirt of the fitter or socket cover 10 is threaded as indicated at 13 and, at the lower edge, has a bead 14.

The reflector is indicated at 15. This reflector is made in the form of a sheet metal porcelain enameled reflector having windows or openings 16 adapted to allow light from the lamp L to pass upwardly. The reflector stamping 15 is here shown as being welded to a stamping 17, as indicated at 18. This stamping supports the reflector. It has a depending flange indicated at 17' and a flat inwardly extending portion 19 and a short upwardly bent flange 20. This flange is welded to a reducer 21 having a flat upper surface indicated at 22. The reflector, stamping 17 and reducer 21 may be a single stamping, if desired. The reducer is connected to a threaded neck or ring 23 (preferably made of sheet copper) of a size to fit inside the threaded end of the socket cover. A gasket 24, composed of material of high coefficient of friction (such as rubber), is interposed between the flange 14 and the platform or flat portion 22 of the reducer 21.

A sheet metal ring or shell 25 (made, for example, of aluminum) is secured to the flat portion 19 of the stamping 17, being held in place by screws 26 threaded into nuts 27. The downwardly flanged portion of the

stamping 25 is threaded, as indicated at 28, to receive the threaded neck 29 of a diffusing glass bowl 30. A gasket 31, in the form of a ring of asbestos (having a low coefficient of friction), is secured in place by prongs on a ring 33.

This fixture is installed by threading the metal neck 23 of the adapter 17-21 into the skirt of the socket cover so as to bring the parts tightly together and to compress the gasket 24. This permanently supports all the metal parts. The glass shade is threaded in place as indicated so as to bring the upper face of the glass against the asbestos gasket 31. This makes a substantially tight dust proof and vapor proof unit from which the downwardly directed light is either directly diffused light or light reflected from the inside of the reflector. A small amount of the light passing through the diffuser is transmitted upwardly through the openings 16.

The removal of the glass shade from the fixture is easily accomplished by merely unthreading it. The friction between the threaded glass part and the threaded shell 28 and asbestos ring 31 is much less than the friction between the parts 22 and 14 in the interposed rubber gasket 24. Hence, the latter named parts do not separate or loosen when one loosens the glass diffuser.

In the larger units, instead of employing the threaded connections 13-23, it is possible to support the metal parts directly from a socket cover. A fragment of such a socket cover is indicated at 40 in Figure 4. The lower edge of this socket cover may be welded to the flange 20, as there indicated.

It is obvious that the invention may be embodied in many forms and constructions within the scope of the claims, and I wish it to be understood that the particular forms shown are but two of the many forms. Various modifications and changes being possible, I do not otherwise limit myself in any way with respect thereto.

I claim:

1. A lighting unit comprising a downwardly acting reflector, a support for the reflector, said support terminating in a threaded neck made of copper, a porcelain enameled socket cover threaded to the neck of the reflector support, a socket in the socket cover, a lamp in the socket, a ring having a depending threaded flange secured to the reflector support, a diffusing glass bowl threaded into the flange and enclosing the lamp, a rubber gasket between the neck and socket cover and an asbestos gasket against which the glass bowl is brought when tightened in place.

2. In a lighting unit, a supporting member in the form of a threaded ring of porce-

lain enameled metal, a threaded neck threaded thereto, a gasket between the threaded parts, a depending threaded flange carried from the neck and of substantially larger diameter than the neck, a glass globe threaded to the flange, and a second gasket against which the end of the globe is brought when the globe is tightened in place, the areas of the parts in contact and the coefficients of friction between them being so related that the first gasket offers more resistance than the second whereby the glass globe may be removed without unthreading the other parts.

3. A lighting fixture comprising a lamp socket, a socket cover having a threaded skirt, a combined reflector and reflector support made of sheet metal and having a threaded neck to fit in the threaded skirt, a downwardly and outwardly flaring reflector and outer connecting portions including two flat areas of different diameters, a gasket between the smaller flat area and the skirt, a plate secured to the outer flat area and having a depending threaded flange above and inside the reflector, a gasket secured to the under surface of the plate, and a glass bowl threaded into the flange and against the second gasket.

4. A lighting fixture comprising a lamp socket, a cover enclosing the socket and having a skirt portion, a downwardly acting reflector, an annular support for the reflector and having a neck portion engaged with the said skirt portion and a depending flange portion of a greater diameter than the said neck portion connecting the reflector, a light diffusing bowl, an annular bowl supporting member secured to the lower side of the reflector support and having a flange portion depending therefrom concentrically inward of the said depending flange portion of the reflector support and engaged with the bowl, and a lamp in the socket and enclosed by the bowl, said reflector having a plurality of light openings spaced about the outer side of the said depending flange portion of the reflector support, and substantially in the plane of the lower edge of the said bowl supporting flange portion for an upward transmission of light diffused by the bowl.

5. The light fixture as set forth in claim 4, wherein the neck portion of the reflector support is in screw threaded connection with the skirt portion of the cover for the lamp socket, and the light diffusing bowl is in similar connection with the depending flange portion of the bowl supporting member.

6. The light fixture as set forth in claim 4, wherein the bowl supporting member is detachably secured to the reflector support.

SHIRLEY R. NAYSMITH.
